UNITED STATES PATENT OFFICE.

HUGH MACINNES, OF JERSEY CITY, NEW JERSEY.

FLEXIBLE SHINGLE.

Application filed February 28, 1923. Serial No. 621,720.

To all whom it may concern:

Be it known that I, HUGH MACINNES, a citizen of the United States, residing at Jersey City, county of Hudson, and State 5 of New Jersey, have invented a certain new and useful Flexible Shingle, of which the following is a specification.

This invention is an improvement in flexible shingles for roofings and sidings, and 10 the object is to retain the marginal portion of said shingle from distortion or curling under the effect of solar heat and exposure to the weather, as well as to facilitate the installation or laying of the shingle.

15 The article is of a composite character, usually comprising a base composed of fibrous material, such as felt, which is waterproofed by impregnating the same with an appropriate agent, like a low melt point asphaltum, and the weather surface of said material is provided with coatings, one of which is usually a high melt point asphaltum, and the other is composed of granular material incorporated with the last mentioned-coating of asphaltum. When installed on a roof, the shingle, composed of materials such as described, is usually free or unrestrained at the margins and it is exposed to heat and moisture, with the result 20 that said free margins will become distorted and curl upwardly, exposing the shingle to wind pressure admitted below said curled up edges, as well as to the entry of rain.

Heretofore it has been proposed to 25 confine the lower exposed corner of a flexible shingle by providing said lower corner with an underlying flap formed by folding the lower corner under the shingle body, and by restoring to the use of a mechanical fastener, 30 such as a pin, attached to the flap and projecting at its ends beyond the respective side edges of the shingle. When installing shingles provided with the under folded corner flap and with the metallic fastener, 35 the workman is required to pull up the individual shingle in order to position it in the required relation to other shingles, and this pulling up operation unfolds or "unravels" the flap, more or less, so that the 40 metallic fastener will work loose in a wind storm, and when said flap becomes unfolded, or unraveled, even slightly, the head lap of the shingle is decreased, with the result that the shingle is not safely applied to exclude 45 rain and wind from beating under the shingle at the side and lower margin thereof.

I have simplified the shingle construction by omitting the flap altogether, and in this invention the lower corner of the shingle is cut off at an angle to the two side edges, the 50 lower cut off edge being straight. A metallic fastener is used for retaining the straight flapless edge of the shingle, said fastener being a bar, pin or rod attached directly to the shingle body, adjacent the 55 straight lower edge thereof, and with the ends protruding beyond the respective side edges of the shingle.

The omission of the flap attains economy in the manufacture of the shingle, both as to 60 material used and the time and labor required to fold the flap; but the straight lower edge affords a line definitely predetermined in which the metallic fastener is applied. The attachment of the metallic fastener directly to the body of the shingle affords a 65 permanent location for said fastener in lieu of a movable or shiftable relation of the fastener to the shingle such as is afforded by the attachment of the fastener to the 70 folded flap of prior shingles.

Other functions and advantages of the invention will appear from the following description taken in connection with the drawings, wherein—

85

Figure 1 is a view showing a number of shingles applied in accordance with my invention.

90

Figure 2 is a detail plan view of the shingle.

Figure 3 is a vertical section on the line 3—3 of Figure 2; and

Figure 4 is a horizontal section on the line 4—4 of Figure 2.

The shingle A is a flat piece of material, 95 substantially square in shape, and composed of a basic layer of material, such as felt, which in the process of making said shingle, is waterproofed by impregnating said layer with a waterproofing agent, such as a low 100 melt point asphalt maintained in a hot semi-liquid condition and within which bath the felt layer is conducted. To the weather surface of the material, is applied two coatings, one composed of a high melt point 105 asphalt and the other of granular material. The surface coating resists the effects of solar heat, and the granular material is pressed into the surface coating so as to become intimately incorporated therewith. 110 The material is prepared economically in sheet form, and the square shingles A are

cut by appropriate mechanism from said sheet.

The shingle is devoid of a flap, or any element resembling said flap, or any equivalent therefor. The lower corner is cut off to produce a straight lower edge, *a*, the latter bisecting the side edges *a'* of the shingle body.

B is the metallic fastener, herein shown 10 as a pin, bar or rod, which is attached directly to the shingle body adjacent the lower cut off corner or straight edge *a*. As shown, the pin, bar or rod passes through the material of the shingle body, at *b* in Figure 4, and the end portions *b'* of said pin, rod or bar are extended beyond the shingle body at the opposite edges *a'* thereof.

In my invention, the construction is simplified and economy attained by the omission 20 of an underlying flap, and the metallic fastener is attached fixedly to the shingle body itself to the end that the metallic fastener occupies a permanent and immovable relation to the shingle, whereby the fastener 25 is precluded from moving out of position in the operation of laying the shingles. In shingles wherein the metallic fastener is attached to an underlying flap, the fastener and the flap are both movable, and subject 30 to the shingles to a change of the lines at which the shingles are to be laid, but in my device, the fastener is in an immovable relation to the straight lower edge, *a*, of the shingle body itself.

35 The shingles are laid with the margins of one shingle in overlapping relation to shingles first applied, and with the end portions *b'* of the fastener pin, or rod, inserted beneath the margins of the underlying shingles, as shown by dotted lines in Figure 1. The straight lower edges of the shingles act 40 as guides in laying the shingles, with the angular corners in a desired relation to and overlapping the edges of the underlying

shingles. The fastener pin or rod of the 45 overlying shingle fits beneath the edges of the shingles below and acts as a retainer in confining the lower corner and the margins of said overlying shingle in such close relation to the underlying shingles as to exclude 50 the entry of rain and wind and to preclude the margins of the overlying shingle from distortion under solar heat and upon exposure to the weather. The attachment of the pin or rod directly to the shingle body 55 to attain an immovable and permanent relation enables the workman to apply the shingle with precision and speedily, for the reason that there is no flap to be pulled up, or to change the lines by unraveling of said 60 flap. Furthermore, the pin or rod being immovably attached to the shingle, said pin or rod will not work loose under wind pressure, nor is there a tendency of the pin or the shingle to become displaced, even 65 slightly, thus effectively excluding the entry of wind and rain beneath the margins of the shingle.

Having thus fully described the invention, what I claim as new and desire to secure by 70 Letters Patent is:

As an improved article of manufacture, a shingle formed of a flat body the under face of which is in the same continuous plane throughout, one edge of the shingle being 75 straight, the body of the shingle having therein a fastener substantially parallel with said straight edge, the ends of the fastener being passed through said body with its end portions extended in opposite directions outwardly beyond the opposite adjacent edges of the shingle body adjacent said straight edge and between the latter and the transverse center line through the shingle.

In testimony whereof I have hereto signed 80 my name this 10th day of February, 1923.

HUGH MACINNES.
